OTHER PUBLICATIONS

Notice of allowance dated Apr. 11, 2017 (2nd NOA) for U.S. Appl. No. 29/500,407 of inventor Andrew Zenoff.

(Continued)

Primary Examiner — Mary Ann Calabrese(74) *Attorney, Agent, or Firm* — Fenwick & West LLP(57) **CLAIM**

The ornamental design for a wearable display device, as shown and described.

DESCRIPTION

FIG. 1 is a top perspective view of the wearable display device showing our new design;

FIG. 2 is a top plan view thereof;

FIG. 3 is a bottom plan view thereof;

FIG. 4 is a left elevation view thereof;

FIG. 5 is a right elevation view thereof;

FIG. 6 is a front elevation view thereof; and,

FIG. 7 is a rear elevation view thereof.

The broken lines show portions of the wearable display device that form no part of the claimed design.

1 Claim, 7 Drawing Sheets# US D849,140 S
